UNITED STATES PATENT OFFICE.

MARCUS L. BROWN, OF DECATUR, GEORGIA.

VENTILATING APPARATUS.

1,319,267.

Specification of Letters Patent.

Patented Oct. 21, 1919.

Application filed February 21, 1919. Serial No. 278,355.

To all whom it may concern:

Be it known that I, MARCUS L. BROWN, a citizen of the United States of America, and resident of Decatur, in the county of Dekalb 5 and State of Georgia, have invented certain new and useful Improvements in Ventilating Apparatus, of which the following is a specification.

This invention relates to ventilators and 10 particularly to means for preventing the accumulation of moisture, gases, injurious vapors or heat in store houses and particularly for ventilating masses of cotton seed when stored in a bin or loft.

15 An object of this invention is to provide novel supporting means and ventilating means to accomplish the result stated, the same to be used in connection with buildings having floors with spaces thereunder or 20 in connection with floors which cannot receive currents of air from below.

A further object of this invention is to 25 provide a ventilator of the character indicated which may be made of different materials and which may be differently shaped according to the requirements in practice.

With the foregoing and other objects in 30 view, the invention consists in the details of construction, and in the arrangement and combination of parts to be hereinafter more fully set forth and claimed.

In describing the invention in detail, reference will be had to the accompanying drawings forming part of this specification 35 in which like characters denote corresponding parts in the several views, and in which—

Figure 1 illustrates a view in elevation, partly in section of a ventilating column 40 embodying one form of the invention;

Fig. 2 illustrates a sectional view on the line 2—2 of Fig. 1;

Fig. 3 illustrates a view in elevation showing a modified foraminous material constituting the sheathing;

Fig. 4 illustrates a vertical sectional view of a ventilating column associated with the air duct adapted to open to the exterior of a building;

50 Fig. 5 illustrates a view in elevation, partly in section of a further modified construction;

Fig. 6 illustrates a view in elevation of a further modification;

55 Fig. 7 illustrates a sectional view on a

line corresponding with the line 7—7 of Fig. 4;

Fig. 8 illustrates a sectional view on the line 8—8 of Fig. 5; and

Fig. 9 illustrates a sectional view on the line 9—9 of Fig. 6.

In these drawings 15 and 16 denotes members of a T-shaped post which constitutes the frame of the column shown in Fig. 1, the member 16 having beveled ends as shown 65 at 17 for engaging the wire netting 18 which, in the present embodiment of the invention, is shown as tubular and tapering from the bottom flange 19 to the top flange 20, it being the purpose of the inventor to 70 have the bottom flange 19 secured to a floor and the top flange 20 connected to a ceiling through which latter an opening may be formed to permit the circulation necessary to ventilate the bin or room in which the 75 column is stationed, and it is also, the purpose of the inventor to have an aperture in the floor, the said aperture being surrounded by the flange 19 so that air may pass from the bottom to the top of the column, and 80 aid in carrying away the heat which might be generated in a pile of cotton seed.

In Fig. 3, the sheathing 21 of the column is made of foraminous material, preferably sheet metal, and it is supported by a frame 85 structure such as is shown in Fig. 4, the difference between the sheathing in Figs. 3 and 4 being that the sheathing 22 in Fig. 4 consists of wire netting.

The frame structure of Figs. 3 and 4 consists of a series of hoops or rings 23 to which the sheathing may be secured by fastenings such as 24 and these hoops or rings 23 are connected together by vertically disposed strips such as 25, any number of which may 95 be employed, and the vertically disposed strips are secured to the rings or hoops by fastenings such as 24 which may pass through the sheathing as well as through the strips and hoops.

In the constructions noted, a bottom flange 26 and a top flange 27 may be employed having the same functions as the flanges 19 and 20 described in connection with the disclosure in Fig. 1.

100 In Fig. 4, however, provision is made for supplying air to the column in an event the ventilator is employed in buildings where the floor is concrete or where it is not supported clear of the ground. When such 110

conditions are encountered, the flange 26 may be placed on the upper side of a duct 28 which may be supported on the floor, and the end or ends of which may project 5 through the wall of a building and communicate with the external atmosphere, so that the circulation of air can be insured through the said duct and through the column. In Fig. 4, I have also shown the 10 top flange as being connected to a ceiling 29 which has an aperture 30 for the passage of air, it being understood that the building may be constructed in any approved way so long as there is provision for the escape of 15 air at the top and for the admission of air at the bottom of the column.

In Fig. 5 a modified construction is illustrated, consisting of a frame 31 of the general structure of the frame illustrated in 20 Fig. 4, the same being supplied with a sheathing of wire netting 32 and flange 33 which latter are also similar to the sheathing and flange shown in Fig. 4, but in the construction shown in Fig. 5, the flange 25 33 is formed as a continuation or at least is carried by a metal jacket or covering 34 which telescopes on the netting 32 fitting the outside of the said netting and extending approximately half way down the post or 30 ventilating column. It is encircled by clamps consisting of bands 35 with outturned ends forming ears 36 and 37 which are drawn together by a bolt 38 so as to exert pressure on the jacket to bind it against the 35 netting 32. This jacket or covering serves two purposes one to increase the draft or suction through the ventilator by confining the heated air while it is passing through the top and its second purpose is to permit 40 the ventilating posts to be adjusted for different heights of lofts after which it can be clamped in position and so held. A ventilating column made in accordance with this last mentioned construction prevents 45 dissipation of the air and confines it somewhat after the manner of a stove pipe and it results in increasing the draft and efficiency.

In Figs. 6 and 9, I have illustrated a still 50 further modification in which the column

comprises angular vertically disposed corner plates 39 held in spaced relation to one another by the bands 40 to form a frame, the said frame being embraced by a wire netting 41 so as to form a column which is 55 square in plan. In this construction, the upper flange 42 and the lower flange 43 are of substantially the same construction as the flanges 19 and 20 except as to their configuration and their functions and purposes 60 are the same.

By reason of the foregoing description and illustration it will be seen that the invention is susceptible of wide margin of modifications and the inventor does not, 65 therefore, wish to be limited with respect to the exact details of construction since the invention resides in the broad idea as well as in the details of construction appearing in the claims.

I claim—

1. In a ventilating device, a frame, foraminous material encircling the frame and spaced therefrom at points in its circumference to form a column having vertical air 75 passages, a flange at the upper end of the column, and a flange at the lower end of the column for anchoring the column.

2. In a ventilating device, a foraminous column, a sleeve constituting an extension 80 of the said column, said sleeve comprising a tubular sheet metal member and clamping bands encircling the said member for causing the said member to frictionally engage the column whereby the said member is 85 telescopically mounted on the column and secured at different positions of adjustment.

3. In a ventilating device, a foraminous column, a sleeve constituting an extension 90 of the said column, said sleeve comprising a tubular sheet metal member and clamping bands encircling the said member for causing the said member to frictionally engage the column whereby the said member is 95 telescopically mounted on the column and secured at different positions of adjustment, and a flange carried by the said member adapted to be secured to a ceiling.

MARCUS L. BROWN.
